(57) **CLAIM**

(22) Filed: **Aug. 7, 2002**

The ornamental design for a base station for computer communication network, as shown and described.

(30) **Foreign Application Priority Data**

DESCRIPTION

Feb. 15, 2002 (JP) 2002-003809

FIG. 1 is a front view showing a base station for computer communication network according to the present invention; FIG. 2 is a rear view showing the base station of FIG. 1; FIG. 3 is a top plan view showing the base station of FIG. 1;

(51) **LOC (7) Cl. 14-02**

FIG. 4 is a bottom plan view showing the base station of FIG. 1;

(52) **U.S. Cl. D14/358**

FIG. 5 is a right side view showing the base station of FIG. 1;
